UNITED STATES PATENT OFFICE.

LOUIS J. HIRT, OF BROOKLINE, MASSACHUSETTS.

GAS-ENGINE.

SPECIFICATION forming part of Letters Patent No. 629,904, dated August 1, 1899.

Application filed July 20, 1897. Serial No. 645,221. (No model.)

To all whom it may concern:

Be it known that I, LOUIS J. HIRT, a citizen of the United States, residing in Brookline, in the county of Norfolk and State of Massachusetts, have invented an Improvement in Gas-Engines, of which the following description, in connection with the accompanying drawings, is a specification, like letters and figures on the drawings representing like parts.

This invention relates to a gas-engine, and has for its object to provide an engine capable at the will of the operator of working as a two-cycle engine having a power-stroke for every revolution of the main shaft or as a four-cycle engine having a power-stroke for alternate revolutions of the main shaft.

In accordance with this invention the engine is provided with novel valves controlling the admission and exhaust of the gas to and from the cylinder and a novel mechanism for operating the valves, which is capable of being worked at the will of the operator to control the flow of gas into and out of the cylinder, so that the engine may be operated either as a two-cycle engine or as a four-cycle engine. These and other features of this invention will be pointed out in the claims at the end of this specification.

Figure 1 is a side elevation of one form of gas-engine embodying this invention; Fig. 2, a top or plan view of the engine shown in Fig. 1; Fig. 3, a detail in section of the igniter, the section being taken on the line 3 3, Fig. 2; Fig. 4, a cross-section on the lines 4 4, Figs. 3 and 2, looking in the direction of the arrow in Fig. 1; Fig. 5, a cross-section on the irregular line 5 5, Fig. 1, looking in the direction of the arrow thereon; Fig. 6, a cross-section on the line 6 6, Fig. 1, looking toward the right; Fig. 7, a horizontal section on the line 7 7, Fig. 1; and Fig. 8, a side elevation of the engine shown in Fig. 2, looking at the opposite side from that shown in Fig. 1.

In the present instance I have chosen to illustrate my invention as a double-acting engine, in which A represents a cylinder secured, as by bolts A', to a frame A², erected upon a base or foundation A³. The cylinder A (see Fig. 7) contains within it a piston a, provided with a piston-rod a' and adapted to be reciprocated in the cylinder A by means of

gas admitted into the cylinder at its opposite ends through the ports a² a^{2a}, which communicate, respectively, with valve-chambers a⁴ a^{4a}, containing balanced piston-rods a⁶ a^{6a}, 55 the said valve-chambers communicating with a single inlet-port a⁸, (see Figs. 1 and 2,) to which in practice the gas-supply pipe is secured. The piston-valves a⁶ a^{6a} are of like construction and are preferably made as will 60 now be described.

The piston-valve a⁶ is vertically arranged, and its lower part or half is of smaller diameter, so as to leave between it and the walls of the cylinder a⁴ an annular passage a¹⁰ for 65 the gases admitted into the said cylinder to encircle the valve and assist in balancing the same. The lower or bottom end of the piston-valve is beveled, as represented in Fig. 4, and cooperates with a beveled seat 2 at the bottom 70 of the port a² to thereby close the communication between the gas inlet or supply a⁸ and the port a². The piston-valve a⁶ is provided with a valve-rod a¹², extended through a suitable stuffing-box a¹³, which forms the bottom 75 of the cylinder a⁴, and the said piston-rod a¹², within the lower part of the cylinder a⁴, is provided with a counterbalancing-piston a¹⁴, the purpose of which is to prevent the valve a⁶ being lifted from its said seat when the 80 engine is running as a two-cycle engine.

The valve-rod a¹² has mounted upon it below the piston-valve a series of perforated disks a¹⁵ to prevent flashing back and which, as shown, are secured between the bottom of 85 the piston-valve and a washer a^{12a}.

The valve-rod a¹², as represented in Figs. 1 and 4, has secured to its lower end a yoke or arm a¹⁶, provided, as shown, with a slot a^{16a}, (see dotted lines, Fig. 4, and full lines, 90 Fig. 1,) into which is extended an arm a¹⁷ on a rock-shaft a¹⁸, having an arm a¹⁹ extended substantially diametrically opposite to the arm a¹⁷ and engaging a depending lug or arm a²⁰ on a lever a²¹ for a purpose as will be described. The yoke or arm a¹⁶ is also engaged by a spring a²², fastened to a stationary part of the engine and, as shown, extended into a slot in the arm or yoke a¹⁶ and which acts under normal conditions to keep the valve a⁶ 100 seated. The valve a⁶ is designed to be automatically governed by the speed of the en-

gine, so as to vary the length of the valve-stroke, and thereby the admission of the gas into the cylinder, and this result may be effected in the following manner.

Referring to Figs. 1, 4, and 6, the lever or arm a^{21} , which engages the rocker-arm a^{19} , is pivoted to the lower end of an arm a^{23} of a bell-crank lever mounted on a shaft or pivot a^{24} and having its arm a^{25} connected by a link a^{26} to an arm a^{27} , fast on a rock-shaft a^{28} , which is supported in suitable bearings a^{31} a^{32} (see Fig. 1) and has a crank or arm a^{29} , (see Fig. 6,) joined by a link a^{30} to a sliding collar a^{33} of a governor G of any usual or desired construction.

The gases admitted into the cylinder A through the port or passage a^2 are designed to pass out from said cylinder through an exhaust-port b into an exhaust-chamber b' , containing an exhaust piston-valve b^2 , the said exhaust-chamber having a main outlet-port b^3 connected to the main exhaust-pipe b^3 . (Shown in Figs. 2 and 5.)

The piston-valve b^2 has its upper end fitted to slide in the valve-cylinder b' , and its lower part or end is made of smaller diameter to leave an annular passage b^5 , so that the exhaust-gases may encircle the valve and substantially balance the same to thereby insure the exhaust-valve working under all conditions and irrespective of the pressure in the cylinder A.

The exhaust-valve b^2 is provided with a valve-rod b^4 , having at its lower end a yoke or slotted arm b^7 , through which extends the end of a lever b^8 , (see Fig. 4,) pivoted at b^9 to a depending arm or bracket b^{10} , secured, as by bolts b^{12} , to the bottom of the cylinder A. The yoke b^7 is also engaged by a spring b^{13} , which normally acts to hold the exhaust-valve b^2 to its seat b^{14} . The gas admitted into the cylinder A after compression, as will be described, is exploded by means of an igniter, preferably of the construction herein shown (see Fig. 3) and consisting of a cylinder c , provided with a conical cap or head c' , having preferably a plurality of vents c^2 , and the said cylinder has a pipe or passage c^4 communicating with the port a^2 . (See Figs. 3 and 7.) The cylinder c contains a piston c^3 , provided with a stem or rod c^5 , having a slotted arm or yoke c^6 (see Fig. 5) engaged by an arm c^7 on a sleeve c^8 , (see Fig. 1,) mounted loosely on a stud or pin c^9 , secured to the frame A², the said lever having an arm c^{10} , which is adapted to be engaged by cams c^{12} c^{13} , (see Figs. 2, 4, and 5,) as will be described. The piston c^3 is normally elevated by the spring c^{14} , attached at one end to the cylinder c and at its other end to the arm c^7 .

The vented cap c' is extended into a pipe c^{15} , provided with a burner tube or jet c^{16} , which in practice is connected to a suitable source of supply for the gas which is continuously burning at the mouth of the tube or jet c^{16} , and thereby keeps the cap c' heated sufficiently hot to ignite the gas admitted into

the cap c' from the port a^2 through the passage c^4 on the downstroke of the piston c^3 . The vent-openings in the cap c' afford opportunity for the piston c^3 to expel the gases out of the cap on the upstroke of the piston, and thereby avoid the accumulation of what may be termed "waste" or "dead" gases in the cap, and consequently insures the ignition of each charge of gas admitted into the cylinder A.

The gas-inlet valve a^6 and its exhaust-valve b^2 are adapted to be operated by double cams c^{45} c^{46} when the engine is operating as a two-cycle engine, and when operating as a four-cycle engine the valve a^6 is operated by a single cam c^{17} and the exhaust-valve b^2 by a single cam c^{18} . These cams are fast on a shaft c^{20} , capable of being moved longitudinally to change the position of the constant and variable cams as desired with relation to the levers connected to the valves.

The shaft c^{20} is rotated by a shaft c^{21} , to which it is connected by a sleeve c^{22} and a key c^{23} , the sleeve being adapted to be moved longitudinally by a lever c^{24} , forked at its end and pivoted at c^{25} and provided with suitable lugs to engage an annular groove in the said sleeve. The lever c^{24} is adapted to be locked in one or the other position in any suitable or desired manner. The shaft c^{21} is driven from the main shaft c^{27} by a spur-gear c^{28} in mesh with a spur-wheel c^{29} , in turn fast to a beveled gear c^{30} , which drives a beveled gear c^{31} , fast on the shaft c^{21} . The spur-wheel c^{29} and gear c^{28} are set two to one, so that the main shaft c^{27} makes two revolutions to one of the shaft c^{21} , whereby single cams may operate the valves once every two revolutions of the main shaft and double cams every revolution.

The piston a' may be connected to the main shaft c^{27} in any suitable or desired manner and is herein shown as connected to a sliding cross-head c^{40} , (see Fig. 1,) joined by a connecting-rod c^{41} to a crank-pin c^{42} on a disk or crank c^{43} , fast on the main shaft.

The engine can be started under load with the double cams c^{15} c^{16} , so that the engine will be operated by gas and air taken from suitable receivers, not herein shown, but such as now employed with two-cycle engines, in which the gas or mixture of gas and air is admitted into the piston-cylinder at each stroke of the piston and is exploded as soon as it is admitted into said cylinder.

When the engine is started and running, it may be converted at the will of the operator into a four-cycle engine by shifting the shaft c^{20} so that the single cams c^{17} c^{18} will operate the valves once every two revolutions, and gas or a mixture of gas and air will be admitted into the piston-cylinder at every other stroke of the piston and exploded at the beginning of the second forward stroke of the piston after being compressed on the return portion of the first stroke of the piston. As a result the engine possesses all the ad-

vantages of a two-cycle engine for starting under a load and of a four-cycle engine for economy when once started.

When the engine is working as a two-cycle engine, the gas-admission valve a^6 and the igniter-piston c^8 are operated substantially simultaneously, so that the gas is ignited as it enters the cylinder, and when working as a four-cycle engine the cams c^{17} and c^{18} are timed so that the gas is first admitted into the cylinder, then compressed, and when compressed it is exploded and expanded and then exhausted.

In the present instance the engine is shown as a double-acting engine, provided at one end of the cylinder A with the inlet-port a^2 and exhaust-port b and at the other end with like ports and parts coöperating therewith, together with an igniter, all of which parts are marked with the same letters as the parts at the opposite end of the cylinder with the affix a added.

If desired, my invention may be embodied in a single-acting engine.

By reference to Fig. 4 it will be seen that the cams c^{15} c^{16} are adapted to engage the upper surface or cross-piece 3 on the end of the lever a^{21} to open the gas-inlet valve a^6 and that the position of the cross-piece 3 with relation to the said cams is determined by the speed of the engine through the governor G, which turns the bell-crank lever on its pivot a^{24} , and thereby moves the lever a^{21} on the arm a^{19} , so as to present more or less of the cross-piece 3 to the action of the cams, whereby more or less of the cams engage the cross-piece and thereby open the gas-inlet valve more or less, according to the speed of the engine.

When the engine is working as a four-cycle engine, the cam c^{17} is shaped or timed to permit the gas-admission valve to cut off the supply of gas before the piston reaches the end of its first stroke, the point of cut-off being variable and controlled by the governor, as above described, thus causing a slight reduction in pressure within the cylinder, which assists the gases to absorb the heat of the cylinder-walls, and consequently reduce the temperature of the same while the engine is in operation and also reduces the clearance necessary to bring the compression-line to the proper pressure, which reduction in clearance permits the expansion to be carried to a maximum degree.

The governor G is driven from the shaft c^{21} , as herein shown, by a bevel-gear c^{50} in mesh with a bevel-pinion c^{51} on the shaft c^{52} of the said governor.

I claim—

1. In a gas-engine, the combination of the following instrumentalities, viz: a working cylinder and piston, inlet and exhaust valves therefor, and an igniter, a main shaft oper-

ated by the piston, and a cam-shaft provided with two sets of cams, one set being arranged to operate the valves and igniter at every revolution of the main shaft, and the other set being arranged to operate them at every other revolution of the main shaft, the cam-shaft being bodily movable to bring either set of cams into operation at will, substantially as described.

2. In a gas-engine, the combination of the following instrumentalities, viz: a cylinder, a piston therein, gas inlet and exhaust balanced piston-valves, levers connected to said valves, two sets of cams to act on said levers and movable with relation thereto at the will of the operator, springs to act on said valves in opposition to said levers, and an igniter co-operating with the gas-inlet valve, substantially as described.

3. In a gas-engine, the combination of the following instrumentalities, viz: a main cylinder, a piston therein, a main shaft to which said piston is connected, gas inlet and exhaust valves provided with valve-rods, levers connected to said valve-rods, a cam-shaft composed of two parts, one of which is movable longitudinally, gearing connecting said cam-shaft to the main shaft, two sets of cams fast on the movable part of said shaft and coöperating one at a time with the levers connected to the valve-rods, means to move the valves in the opposite direction to the cams, and an igniter co-operating with the gas-inlet valve, substantially as described.

4. In a gas-engine, the combination of the following instrumentalities, viz: a main cylinder, a piston therein, valve-cylinders communicating with said main cylinder, balanced piston gas inlet and exhaust valves in said valve-cylinders provided with valve-rods, levers connected to said valve-rods, an igniter-cylinder connected to the cylinder of the gas-inlet valve and provided with a vent for the consumed gases, a piston in said igniter-cylinder provided with a piston-rod, a lever connected to said piston-rod, a main shaft to which the main piston is connected, a cam-shaft connected to said main shaft to be rotated thereby and provided with a longitudinally-movable section, two sets of cams fast on said movable section of the cam-shaft and coöperating with the levers connected to the said gas inlet and exhaust valves and to the igniter-piston, and a governor connected to the operating-lever for the gas-admission valve, substantially as described.

In testimony whereof I have signed my name to this specification in the presence of two subscribing witnesses.

LOUIS J. HIRT.
